UNITED STATES PATENT OFFICE

ROY H. BREYFOGLE, OF WHITE PIGEON, MICHIGAN

TUB BEATER

Application filed February 3, 1927. Serial No. 165,582.

The present improvements relate more particularly to a beater of the continuous type for reducing stock to pulp, commonly known as a tub beater.

5 The invention relates more specifically to tub beaters of the continuous type in which pulp which has been reduced to the desired size or fineness, is continuously withdrawn from the moving mass of pulp in the beater, 10 while regulated quantities of fresh charge are added, either continuously or intermittently without interrupting the continuous operation of the machine.

In its more specific embodiment, the invention 15 comprises a perforated plate forming part of, or placed in the hood normally disposed over the beater roll, through which the pulp, which has been reduced to the degree of fineness desired, is discharged by the centrifugal rotary action of the beater.

As a feature of the present invention, this perforated plate is disposed immediately above, or on the same side of the beater roll as the usual back fall.

25 The advantage accruing to the placing of this perforated plate on the same side of the roll as is located the back fall, is that the maximum centrifugal force created by the rotation of the beater roll in combination with 30 the narrow space between the circumference of the beater roll and the surface of the back fall is utilized for the purpose of throwing said pulp against the under surface of the perforated plate, with a minimum loss of said force.

35 Pulp passing through said perforated plate, is withdrawn through a discharge pipe communicating with the usual stuff chest or other obvious instrumentality.

40 Many other objects and advantages will be more particularly apparent from the following description.

In the drawings, Fig. 1 is an enlarged top plan view of a tub beater equipped with my invention.

45 Fig. 2 is a partly side elevational view and partly a cross section taken on line 2—2 of Fig. 1.

50 Referring more in detail to the drawings, 1 represents the usual tank of a tub beater

which is provided with the usual mid feather 2 of suitable length. A shaft 3 rotated by means of power imparted to the pulley wheel 4 carried thereby projects across the interior of the tub 1 and on one side of the mid feather 2 carries the beater roll 5. This beater roll 5 is provided with the usual cutting knives 6 projecting from its surface, and designed to coact with a fixed member 7 supported in the customary manner at the bottom of the tank 1 by means of the support 8. The back fall 9 extends upwardly adjacent to, but at an increasing distance from the surface of the beating roll 5 having its upper outer end carried to a height approximately at the level of the center line of said roll, from whence it extends backward at an approximate angle of about 45 degrees to the bottom of the tank. This back fall 9 is of any standard construction.

55 A hood 10 is suitably supported on the upper annular edge of the tank 1, which hood may be of any shape or design as will be found most suitable and convenient. This hood may be provided with the rings 11, for the purpose of permitting raising by suitable instrumentality. The hood is provided with side walls 12, which define a space in which pulp is received and discharged through either of the discharge pipes 13 to a suitable 60 stuff chest or other instrumentality.

65 As a feature of the present invention, on the same side of the drum 5 as is located the back fall 9, I provide above said back fall a perforated plate 14. This plate 14 has perforations 15, the size and number of which are predetermined to permit only the pulp which has been reduced to the desired fineness and size to pass therethrough. The perforations 15 in this plate 14 are preferably 70 disposed immediately above the back fall 9, and in any event, are disposed on the same side of the beater roll as the back fall 9 for the purpose of utilizing the centrifugal force set up by the rotation of the beating roll to cause 75

80 the pulp to be thrown upwardly against the under surface of the plate, at which time the pulp which has been reduced to desired size, passes through the perforations. It is obvious 85 that there is a minimum of loss of force by 90

positioning the perforations immediately in the path of the pulpy mass issuing from the confined space between the surface of the beating roll and the back fall.

5 The pulp passing through the perforations will collect in the lower part of the space 15' discharging through the outlet 13. In case the stuff chest or other instrumentality is receiving an excess of pulp, the valve comprising the weir gate 16 may be manipulated to 10 clear the opening 17 in an end wall of the hood thus permitting the overflow to pass into the conduit 18 which returns said pulp to the mass in the tank 1.

15 I am aware that heretofore, beaters of the continuous type have been known in the prior art. I am also aware that the prior art discloses continuous beaters utilizing a perforated back fall and utilizing a perforated plate on the opposite side of the beater roll from that on which the back fall is located 20 in combination with an element for removing the larger pieces which might adhere to the perforated surface.

25 The present invention has obvious advantages thereover, among which may be pointed out the greater capacity due to taking advantage of the maximum centrifugal force set up by the revolving beater roll 5, and the 30 elimination of the necessity for mechanical scraping or cleaning refuse, that is, the foreign matter of larger size than the perforations, which is objectionable in the particular grade of stock which it is desired to produce.

35 It has been found in use that the centrifugal force set up by the beating roll 5 is sufficient without mechanical means, to clean or remove said larger size particles from the 40 surface of the perforated plate. The insufficiently reduced pulp is thrown back into the beating engine while the sufficiently reduced fibres pass through the perforations and on to the stuff chest. The operation is 45 continuous, and highly efficient.

45 I claim as my invention:

50 1. A pulping machine comprising a beater tub, a beater roll mounted for rotation in said tub, a back fall on one side of said roll and slightly spaced therefrom, a perforated 55 strainer element mounted in the upper portion of said tub on the back fall side of said roll and disposed directly over the space between said roll and back fall, and means for conducting away the material discharged through said element.

60 2. A pulping machine comprising a beater tub, a beater roll mounted for rotation in said tub, a back fall on one side of said roll and slightly spaced therefrom, a perforated 65 plate mounted in the upper portion of said tub on the back fall side of said roll and disposed directly over the space between said roll and back fall and substantially at right angles to the direction of discharge of ma-

terial from said space, and means for carrying away the material discharged through said plate.

3. A pulping machine comprising a beater tub, a beater roll mounted for rotation in said tub, a back fall on one side of said roll and slightly spaced therefrom, a perforated plate mounted in the upper portion of said tub and extending from a point above said roll to a point beyond the top of said back fall, and means on the side of said plate opposite the roll for conducting away material discharged through the plate.

ROY H. BREYFOGLE.
